UNITED STATES PATENT OFFICE.

WILLIAM C. NORCROSS, OF TERRE HAUTE, INDIANA.

ATTACHMENT FOR JOLT-RAMMING MOLDING-MACHINES.

1,316,502.

Specification of Letters Patent. Patented Sept. 16, 1919.

Application filed February 10, 1919. Serial No. 276,136.

To all whom it may concern:

Be it known that I, WILLIAM C. NORCROSS, a citizen of the United States, residing at Terre Haute, in the county of Vigo and 5 State of Indiana, have invented certain new and useful Improvements in Attachments for Jolt-Ramming Molding-Machines, of which the following is a specification.

This invention relates to attachments for 10 jolt-ramming molding machines.

The object of the present invention is the prevention or neutralization of the transmission from a jolt-ramming molding machine of secondary shocks or vibrations and, 15 generally, to prevent the mold from receiving all possible recoils, vibrations, and movements other than such as will effect the settling or "ramming" of the sand in the mold.

The invention is designed, further, to prevent 20 damage in some instances by the cracking of the mold after it has been rammed to the desired density.

The recoil, vibrations or reactions which are set up in jolt-ramming machines, particularly 25 in those machines which have long tables, may become sufficiently violent to prevent ramming or settling of sand in the mold and thus defeat the object of jolting the mold. In any jolt-ramming machine, 30 even the smaller sizes, secondary shocks or vibrations have a tendency to prevent completion of the ramming action or to undo it. Secondary vibrations set up in the bars of the flask cause the sand to separate from 35 the bars and drop away.

My invention consists in cushioning or shock-absorbing means located above the impact surfaces of a jolt-ramming machine for the purpose of absorbing the secondary 40 recoils, vibrations, and movements due to the jolting action when the impact surfaces engage, thereby accomplishing the objects hereinbefore set forth.

My invention also consists in a cushion or 45 shock-absorber on top of the table of the jolt-ramming machine, said cushion or shock-absorber being directly underneath the pattern and mold. In other words, the cushion or insulation is interposed between 50 the pattern and mold and the jolting table on which they are supported. A sheet of rubber, rubber fabric, cork matting, linoleum, spongy wood, or any other suitable material or cushion, whether merely a sheet, 55 or specially formed, may be employed in

carrying out my invention. The invention is not limited to use in connection with any particular jolt-ramming machine nor to the precise location specified but it should be arranged above the impact surfaces of the machine so that, while not interfering with the sharpness of the jolting action, it will, nevertheless, absorb secondary vibrations, recoils and movements. By way of illustration, the invention may be provided on the 60 jolting table of the machines of any of my patents as, for instance, 1,194,059, August 8, 1916; 1,224,407, May 1, 1917; 1,245,955, November 6, 1917; 1,264,427, April 30, 1918; 1,274,752, August 6, 1918. 70

The accompanying drawing is a vertical section through one of my jolt-ramming molding machines showing how the invention may be applied to the table thereof and the pattern plate, flask and mold supported 75 thereon.

In the drawing the invention is shown applied to one of my jolt-ramming machines, but it is not limited to use in connection with any particular machine nor to 80 being located precisely as shown. The base is shown at 1, the cylinder at 2; jolting piston, 3; automatic valve, 4, and the jolting table appears at 5.

Heretofore the flask 6 and pattern plate 7 85 have rested directly upon the upper face of the jolting table 5. Secondary shocks or vibrations have heretofore been set up in the flask, the pattern plate, and in the bars (not shown) of the flask. As a result of the secondary 90 shocks or vibrations, the work of ramming the mold has been interfered with or undone and there has, in some instances, been a tendency to crack the mold after it has been rammed to the desired density; 95 also, the bars of the flask have tended to cause the sand to separate from them and drop away. In the case of large tables, vibrations or reactions have been set up which have interfered seriously with the proper 100 settling of the sand.

My object being to prevent the recoils, vibrations, reactions and other movements which will not contribute to the desired settling or ramming of the sand by the sudden 105 arresting of the fall of the piston and table, I propose to cushion the pattern flask and mold. To that end I provide a cushion, preferably in the form of one or more layers or sheets, 8, placed in some suitable position 110

above the impact surfaces of the machine and disposed at a point between the position of said impact surfaces and the mold flask or other material-container on the table 5. 5 One convenient embodiment of the invention is that shown, where the cushion 8 is located directly on the table 5 and forms an intermediate support for the flask, pattern plate and mold. The flask, pattern plate and mold 10 are thereby cushioned and when the jarring action occurs due to the fall of the piston and table and their sudden arrest, secondary shocks, vibrations or reactions in the flask, pattern plate, bars and mold, are prevented. 15 and the jarring action is a primary one which tends only to cause the sand to settle or ram in the mold.

I do not limit myself to any particular cushion nor to the location thereof in the 20 position shown in the drawings. Sheet rubber, rubber fabric, or substances of a similar cushioning nature, cork matting, linoleum, or spongy wood may be employed. The cushion may be otherwise disposed provided 25 it is above the impact surfaces of the jolting machine.

What I claim is:—

1. A cushioning or shock absorbing attachment interposed between the table of a jolt-ramming machine and the flask, and mold supported by said table. 30
2. The combination with the table of the jolt-ramming machine and the pattern plate, flask and mold supported thereby, of a flat shock-absorbing cushion interposed between the table and the mold. 35
3. The method of preventing secondary vibrations, shocks, recoils and reactions in the mold material while being rammed, consisting in imparting jolt or jar to the mold 40 through an intermediate cushioning medium.
4. A cushioning or shock-absorbing attachment for a jolt-ramming machine, located in a position between the piston of such machine and the mold flask. 45
5. An attachment for a jolt-ramming machine located above the impact surfaces of the machine to absorb the secondary recoils, vibrations and movements due to the jolting action. 50

In testimony whereof I affix my signature.
WILLIAM C. NORCROSS.
